UNITED STATES PATENT OFFICE.

JOSHUA C. CONRAD, OF CEMENT, OKLAHOMA.

COTTON-HULLER.

Specification of Letters Patent. Patented May 11, 1915.

1,139,345.

Application filed January 15, 1914. Serial No. 812,259.

To all whom it may concern:

Be it known that I, JOSHUA C. CONRAD, a citizen of the United States, and a resident of Cement, in the county of Caddo and State 5 of Oklahoma, have made certain new and useful Improvements in Cotton-Hullers, of which the following is a specification.

My invention relates to improvements in devices for separating hulls from cotton, 10 and it consists in the combinations, constructions and arrangements herein described and claimed.

An object of my invention is to provide a device by means of which the cotton may 15 be thoroughly cleaned of the hulls, the former being passed from the machine and the latter also being conveyed away from the interior of the machine.

A further object of my invention is to 20 provide a novel form of feed mechanism for the cotton huller.

A further object of my invention is to 25 provide a novel form of saw cylinder for separating the cotton.

Other objects and advantages will appear 30 in the following specification, and the novel features of the invention will be particularly pointed out in the appended claims.

My invention is illustrated in the accompanying drawings forming part of this application, in which—

Figure 1 is a face view of the device showing the driving mechanism for the cylinders, brushes, beaters, etc., Fig. 2 is a vertical section through the device, Fig. 3 is a longitudinal section through a portion of the device showing one of the saw cylinders, Fig. 4 is a fragmentary detail view of a portion of the device, Fig. 5 is a face view of a portion of a modified form of saw cylinder, and Fig. 6 is a section along the line 6—6 of Fig. 5.

In carrying out my invention I provide a rectangular box or casing 1. At the top 45 of this casing and discharging into the same, is a hopper 2. The hopper is designed to be situated near, and to receive the contents of, a boll breaking and cleaning machine.

Referring now particularly to Fig. 2, it 50 will be seen that in the upper part of the casing 1 is disposed a pair of fluted spiked rollers 3 and 3' respectively, the former on a shaft 4 and the latter on a shaft 4'. Be-

low the rollers 3 and 3' are a pair of beaters 5 and 5' mounted on shafts 6 and 6' respectively. Smaller beaters 7 and 7' on shafts 8 and 8' respectively are below and to one side of the beaters 5. In practical alignment with the shafts 6 and 6' of the beaters 5, are the shafts 9 and 9' which support the saw cylinders. The saw cylinders are made preferably in the form shown in Fig. 3. In this figure it will be seen that the shaft 9 bears a series of saw disks 10 which are spaced apart by blocks 11. These blocks 65 extend nearly to the edge of the disks, the teeth of the saw disks projecting beyond the blocks as shown in Fig. 2. Instead of making the saw cylinder in the manner shown in Fig. 3, I may make it in the form shown 70 in Figs. 5 and 6. To this end, a cylinder 12 of sheet metal, such as sheet steel, is punched with V-shaped projections 13 extending outwardly and forwardly in the direction of rotation of the cylinder. Either of these 75 forms, *i. e.*, that shown in Figs. 3 or 5, may be used. Between the saw cylinders and the feed rolls are disposed brushes 14 and 14' mounted on shafts 15 and 15' respectively, while other brushes 16 and 16' on shafts 17 80 and 17' respectively, are disposed so as to engage the teeth of the saw. Chutes 18 and 18' are disposed below the brushes 16 and 16' respectively. Below each of the saw cylinders are picker rollers 19 and 19' on 85 shafts 20 and 20' respectively. These rollers are designed to pass the hulls down the inclines 21 and 21' to the troughs 22 and 22' where the conveyers 23 and 23' pass the hulls out of the machine. Below the shaft 9 on one side of the machine, are the shafts 9^x and 9^y, each bearing saw cylinders 10^x and 10^y similar to the saws 10. On the opposite side of the machine are the saw cylinders 10^{x'} and 10^{y'}. Brushes 16^x and 16^y 95 mounted on shafts 17^x and 17^y are disposed below the brush 16 while similar brushes 16^{x'} and 16^{y'} are disposed on the opposite side. The rollers 19^x and 19^y, 19^{x'} and 19^{y'} correspond to the rollers 19 and 19' respectively. Below the beaters 5 and in alignment therewith are the beaters 5^x and 5^y, while similar beaters 5^{x'} and 5^{y'} are below the beater 5'. Below the brushes 14 and in vertical alignment therewith are the corresponding brushes 14^x and 14^y, each of these 100 105

brushes being protected by housings 21* which form extensions of the chutes 21. On the other side of the device are the brushes 14* and 14'. Below the beaters 7 and 7' and in alignment therewith are the small beaters 7* and 7' respectively. To one side and below the beaters 5* and 5' are conveyers 30 and 30' respectively which are above the partition 31 and which are designed to carry the load next to the picker rollers 19* and 19'. The partition 31 is provided with openings 33 at the discharge end of the conveyer so that any foreign substances may pass out of the machine.

Referring now particularly to Fig. 1, I have shown therein the drive wheels 24 and 24'. The drive wheel 24 is on a shaft 25 bearing a pulley 26. The shaft 9 of the upper saw cylinder bears a pulley 27 and a sprocket wheel 28 (see Fig. 3). A belt 29 passes over the pulley 26, thence around a pulley 30 on the shaft 15, thence around a pulley 31 on the shaft 17, thence around the pulley 27 and back over the pulley 26. The belt is designed to be driven in the direction shown by the arrows, thus rotating the brushes 14 and 16 and the saws 10 in the direction shown in Fig. 2. Belts 29* and 29' drive the saws and brushes corresponding to the brushes 15 and 16 in the same manner as that already described. A sprocket chain 33 passes over the sprocket wheel 28, thence over a sprocket wheel 34 on the shaft 20 of the roller 19, driving the roller in the direction shown in Fig. 2. Sprocket wheels 33* and 33' perform similar offices for their respective rollers. A belt 36 passes over the pulley 24 and thence over a pulley 35 on the shaft 6 driving the beater. A second pulley 36 on the shaft 6 drives a belt 37 which passes around a pulley 38 on the shaft 6* of the lower beater 5*, thence over a pulley 40 on the shaft 8* of the beater 7*, thence over a pulley 41 on the shaft 8 of the small beater 7, thence over the pulley 36. A belt 42 passes over a pulley 43 on the shaft 6* of the beater 7* and around the pulleys 38 and 40. The rollers, brushes, and beaters on the opposite side of the machine 50 are driven in precisely the same manner. On the shaft 4 of the roller 3 is a gear 44 having teeth 45 beveled on one edge. The gear 44 is designed to mesh with the gear 44' on the shaft 4'. Arranged to engage the teeth of the gear 44 is a pawl 46 which is pivoted to a lever 47 mounted on a fulcrum 48. The pawl 46 is pressed against the teeth by a spring 49 which bears a roller 50. A pawl 46' is designed to engage the gear 44' being pivoted to the lever 47 on the opposite side of the fulcrum 48. An eccentric 51 on a drive shaft 52 operates the lever 47 by means of a telescopic rod 53 which is pivotally connected to the lever. This rod may be extended and clamped by means of a set

screw 54. The lever is provided with a series of openings 55, the upper end of the rod being designed to be attached to the lever at any one of these openings.

From the foregoing description of the various parts of the device the operation thereof may be readily understood.

The cotton is fed into the hopper 2 from the boll machine (not shown) and passes down between the two fluted spiked rollers 3 and 3'. These rollers are operated by the gears 44 and 44' in the manner already described and feed the cotton down upon the beaters 5 and 5'. These are revolving rapidly and throw the cotton and the hulls 80 against the rapidly revolving saw cylinders where the cotton is caught up by the teeth. As the cotton is carried around by the saws it comes in contact with the brushes 15 and 15' which tends to sweep the hulls from the cotton. The cotton is carried on around by the saw until it meets the brushes such as those shown at 16 and 16' which are revolving at a high rate of speed and which, therefore, tend to clean the saws and to deposit 90 the cotton on the chutes 18 and 18' from whence it is delivered outside the machine. Part of the cotton and the hulls will fall down upon the small beaters 7 and 7' which tend to throw it onto the picker rolls 19 and 19'. The latter catch up the cotton and deliver it to the saws, while the hulls are passed over the picker rolls and down the chutes 21 and 21' to the conveyers 22 and 22' which convey the hulls out of the machine.

In Fig. 2 I have shown three tiers of beaters, saw brushes and picker rolls corresponding to the members 5, 7, 10, 15, 16, and 19. Each of these devices acts in precisely the same manner upon the cotton and hulls coming to it as the one above it. It is obvious that the proportion of hulls which is carried out by the lowermost conveyers 23* and 23' is greater than that carried out by the upper conveyers. On the contrary, most of the cotton will be discharged in the upper part of the machine.

The use of a machine of this kind results in a very efficient separation of the hulls from the cotton owing to the fact that no one set of devices has to accomplish the entire hulling of the cotton. It will be apparent that where part of the cotton is separated out by the upper tier of devices and where part of the hulls are also separated out the lower tiers will be less liable to become clogged and will therefore tend to make a more perfect separation.

It is obvious that the machine may be divided at its center and only one division or side used, or one section may be used as feeder for a separate gin stand.

I claim:

1. In a cotton huller, a casing, a feed hop-

- per carried thereby, means for feeding the cotton and hulls from said hopper, a beater disposed below said feeding means, a saw cylinder disposed at one side of said beater and arranged to receive the cotton thrown from the beater, and a revolving brush for cleaning the cotton from the saws. 5
2. In a cotton huller, a casing, a feed hopper carried thereby, means for feeding the cotton and hulls from said hopper, a beater disposed below said feeding means, a saw cylinder disposed at one side of said beater and arranged to receive the cotton thrown from the beater, a revolving brush for cleaning the cotton from the saws, a brush arranged to revolve against the saw teeth for brushing the hulls from the cotton caught up by the saws, an auxiliary beater disposed below and substantially midway between 15 said first named beater and said saw cylinder for deflecting the cotton and hulls passing the first named beater, and a picker roll disposed below the saw cylinders for receiving the cotton and hulls deflected by said auxiliary beater, said picker roll being in close engagement with said saws. 20
3. In a cotton huller, a casing, a feed hopper carried thereby, means for feeding the cotton and hulls from said hopper, a beater disposed below said feeding means, a saw cylinder disposed at one side of said beater and arranged to receive the cotton thrown from the beater, a revolving brush for cleaning the cotton from the saws, a brush arranged to revolve against the saw teeth for brushing the hulls from the cotton caught up by the saws, an auxiliary beater disposed below and substantially midway between 35 said first named beater and said saw cylinder for deflecting the cotton and hulls passing the first named beater, a picker roll disposed below the saw cylinders for receiving the cotton and hulls deflected by said auxiliary beater, said picker roll being in close engagement with said saws, an inclined chute disposed below said picker roll, a trough at one end of said inclined chute, and a conveyer disposed in said trough. 40
4. In a cotton huller, a casing, a feed hopper carried thereby, a pair of feed rollers disposed underneath said feed hopper, a plurality of pairs of rotary beaters disposed underneath said feed roll, the axes of the beaters of each pair being in horizontal alinement, and the axes of the corresponding beaters of the several pairs being in vertical alinement, and a saw cylinder disposed at one side of each of said beaters. 55
5. In a cotton huller, a casing, a feed hopper carried thereby, a pair of feed rollers disposed underneath said feed hopper, a plurality of pairs of rotary beaters disposed underneath said feed roll, the axes of the beaters of each pair being in horizontal alinement, and the axes of the corresponding beaters of the several pairs being in vertical alinement, the individual beaters of each pair being spaced slightly apart and the spaces between the various pairs of beaters being in substantially vertical alinement with the mouth of the hopper, a saw cylinder disposed at one side of each of said beaters. 65
- ing beaters of the several pairs being in vertical alinement, and a saw cylinder disposed at one side of each of said beaters, the axes of the saw cylinders corresponding to any pair of beaters being in horizontal alinement with the axes of the beaters. 70
6. In a cotton huller, a casing, a feed hopper carried thereby, a pair of feed rollers disposed underneath said feed hopper, a plurality of pairs of rotary beaters disposed underneath said feed roll, the axes of the beaters of each pair being in horizontal alinement, and the axes of the corresponding beaters of the several pairs being in vertical alinement, and a saw cylinder disposed at one side of each of said beaters, the axes of the saw cylinders corresponding to any pair of beaters being in horizontal alinement with the axes of the beaters, and the axes of the various saw cylinders on the same side of the beaters being in vertical alinement. 75
7. In a cotton huller, a casing, a feed hopper carried thereby, a pair of feed rollers disposed underneath said feed hopper, a plurality of pairs of rotary beaters disposed underneath said feed roll, the axes of the beaters of each pair being in horizontal alinement, and the axes of the corresponding beaters of the several pairs being in vertical alinement, a saw cylinder disposed at one side of each of said beaters, the axes of the saw cylinders corresponding to any pair of beaters being in horizontal alinement with the axes of the beaters, and the axes of the various saw cylinders on the same side of the beaters being in vertical alinement, a brush for removing the cotton from the saws of each saw cylinder, and a conveyer disposed beneath each saw cylinder for removing hulls. 80
8. In a cotton huller, a casing, a feed hopper carried thereby, means for feeding cotton and hulls from said huller, a pair of beaters disposed below the feed hopper, said beaters being slightly spaced apart and the adjacent edges of the beaters being substantially in vertical alinement with the mouth of the hopper, the axis of each of the beaters being in horizontal alinement, and a saw cylinder disposed at one side of each of said beaters. 90
9. In a cotton huller, a casing, a feed hopper carried thereby, a pair of feed rollers disposed underneath said hopper, a plurality of pairs of rotary beaters disposed underneath said feed roller, the axis of the beaters of each pair being in horizontal alinement, and the axis of the corresponding beaters of the several pairs being in vertical alinement, the individual beaters of each pair being spaced slightly apart and the spaces between the various pairs of beaters being in substantially vertical alinement with the mouth of the hopper, a saw cylinder disposed at one side of each of said beaters. 100
10. In a cotton huller, a casing, a feed hopper carried thereby, a pair of feed rollers disposed underneath said hopper, a plurality of pairs of rotary beaters disposed underneath said feed roller, the axis of the beaters of each pair being in horizontal alinement, and the axis of the corresponding beaters of the several pairs being in vertical alinement, the individual beaters of each pair being spaced slightly apart and the spaces between the various pairs of beaters being in substantially vertical alinement with the mouth of the hopper, a saw cylinder disposed at one side of each of said beaters. 110
11. In a cotton huller, a casing, a feed hopper carried thereby, a pair of feed rollers disposed underneath said hopper, a plurality of pairs of rotary beaters disposed underneath said feed roller, the axis of the beaters of each pair being in horizontal alinement, and the axis of the corresponding beaters of the several pairs being in vertical alinement, the individual beaters of each pair being spaced slightly apart and the spaces between the various pairs of beaters being in substantially vertical alinement with the mouth of the hopper, a saw cylinder disposed at one side of each of said beaters. 120
12. In a cotton huller, a casing, a feed hopper carried thereby, a pair of feed rollers disposed underneath said hopper, a plurality of pairs of rotary beaters disposed underneath said feed roller, the axis of the beaters of each pair being in horizontal alinement, and the axis of the corresponding beaters of the several pairs being in vertical alinement, the individual beaters of each pair being spaced slightly apart and the spaces between the various pairs of beaters being in substantially vertical alinement with the mouth of the hopper, a saw cylinder disposed at one side of each of said beaters. 125
13. In a cotton huller, a casing, a feed hopper carried thereby, a pair of feed rollers disposed underneath said hopper, a plurality of pairs of rotary beaters disposed underneath said feed roller, the axis of the beaters of each pair being in horizontal alinement, and the axis of the corresponding beaters of the several pairs being in vertical alinement, the individual beaters of each pair being spaced slightly apart and the spaces between the various pairs of beaters being in substantially vertical alinement with the mouth of the hopper, a saw cylinder disposed at one side of each of said beaters. 130

der disposed at one side of each of said beaters, the axis of the saw cylinders corresponding to any pair of beaters being in horizontal alinement with the axis of the beaters, and the axis of the various saw cylinders on the same side of the beaters being in vertical alinement, a brush for re-

moving the cotton from the saws of each saw cylinder, and a conveyer disposed beneath each saw cylinder for removing hulls.

JOSHUA C. CONRAD.
